Patented Nov. 22, 1955

176,153

AUTOMOBILE SIGNALLING DEVICE

Thomas D. Pellegrino, Floral Park, N. Y.

Application December 2, 1954, Serial No. 33,370

Term of patent 14 years

(Cl. D72—1)

Fig. 1

Fig. 2

Fig. 3

Figure 1 is a perspective view of an automobile signalling device embodying my new design;

Figure 2 is a side view in elevation thereof, the opposite side view being similar; and

Figure 3 is a front view in elevation thereof.

I claim:

The ornamental design for an automobile signalling device, as shown and described.
